UNITED STATES PATENT OFFICE.

WILLIAM E. MONTGOMERY, OF LA JUNTA, COLORADO.

MEDICAL APPLICATOR.

Application filed October 13, 1923. Serial No. 668,324.

This invention relates to improvements in means for maintaining electrical applicators or the like in supported relation upon a person's body during a treatment.

5 The primary object of this invention is the provision of a novel type of medical applicator having improved means for supporting it upon a person's body during treatment.

10 A further object of this invention is the provision of an applicator of the above mentioned character, preferably in the form of an electrode, having vacuum means cooperating therewith to facilitate its retention upon a person's body during treatment.

15 A further object of this invention is the provision of an applicator of the above mentioned character embodying vacuum means to facilitate the retention of the applicator upon the body during treatment, without liability of causing pain or undesirable results incident to action of the vacuum.

20 A further object of this invention is the provision of an electrode of the above mentioned character which has means therein for supporting a liquid, such as an antiseptic, anæsthetic, or the like, against that part of the anatomy with which the applicator is in contact.

25 30 A further object of this invention is the provision of an electrode device of the above mentioned character having means cooperating therewith to most effectively permit the retention of the device upon a person's anatomy by means of a vacuum, and so that an electrical current may be conveyed over a relatively large area of the anatomy with which the applicator is in contact.

35 Other objects and advantages of this invention will be apparent during the course of the following detailed description.

40 In the accompanying drawings, forming a part of this specification, and wherein similar reference characters designate corresponding parts throughout the several views,

45 Figure 1 is a plan view of the improved applicator, showing certain novel structural details thereof.

50 Figure 2 is a fragmentary view of the improved applicator, showing the same in cross section to disclose novel structural features thereof.

55 Figure 3 is a cross sectional view taken through a modified form of applicator, showing novel details thereof.

Figure 4 is a plan view of a further modified form of improved applicator.

Figure 5 is a cross sectional view taken substantially on the line 5—5 of Figure 4.

Figure 6 is a cross sectional view taken 60 through a fourth form of the applicator, showing novel features thereof.

Figure 7 is a face view of the applicator illustrated in Figure 6.

Figure 8 is an inside plan view of the 65 pad construction of the applicator, showing more particularly the means by which a novel protecting sanitary cloth may be supported thereabout.

Figure 9 is a fragmentary view showing 70 one means by which a vacuum may be created in the applicator to effect its support upon a person's anatomy.

75 In the drawings, wherein for the purpose of illustration are shown several forms which the invention may assume, the letter A may generally designate a form of the invention used for relatively small electrodes or applicators; B an economical form of applicator; C a third form of applicator; 80 and D a fourth form of applicator.

85 Each of the applicators, A, B, C and D may include a supporting casing 10; pad arrangement 11 for cooperation therewith; and means E to form a vacuum in the casing 10.

90 Referring to the form of invention A, the casing 10 thereof may preferably include the head portion 12, which is preferably of metal, although it may be of insulating material, and which is centrally provided with an opening 15 therein which communicates with a chamber 16 formed inwardly of the forward face of the head or disc 12.

95 A substantially J-shaped tube 17 may lead rearwardly, having a passageway 19 therein which communicates with the opening 15; the tube 17 being, of course, disposed on the opposite side of the head 12 from that in which the chamber 16 is formed.

100 An attaching ring 20 is preferably threadably connected exterior to the head 12, providing an inwardly extending annular flange 21 which is adapted to overlie the chambered face of the head 12 to retain the pad arrangement 11 in place.

105 The pad arrangement 11 may include an absorbent and porous portion 23, of wool, fabric, asbestos, or other material, and an outer foraminous screen 24; the screen 24 110

and absorbent portion 23 being clamped in place across the chamber 16 of the electrode head 12 by means of the attaching ring 20, so that a well defined pocket or chamber is provided rearwardly of the pad 11.

If the supporting casing 10 is formed of metal a terminal 25 may be connected thereto, as to the tube 17, to which an electric conducting wire 26 may be suitably clamped.

- 10 It will be well understood by those skilled in the art to which this invention relates that the applicator A is, in fact, one electrode for an electric current, which is to be applied on some part of a person's anatomy for the treatment of an affliction. The other electrode for the person may assume various shapes, such as a similarly formed applicator, or it may be a receptacle having water therein; it being understood 15 that the applicator A is either the positive or negative electrode.

Referring to the means E for creation of a vacuum within the chamber 16, the same may be of any type of construction which 20 will create a vacuum. The most economical form of construction will be that of providing an air exhausting bulb 27, of rubber, or like collapsible material, which has a rubber or flexible tube 28 connected therewith and with the tube 17 of the applicator A. The device A when to be used is placed upon the patient's afflicted body or member, at the desired place, the air being partially exhausted from the chamber 16 by collapsing of said bulb to allow it to enter the bulb 27. As the attaching ring 20 of the casing 10 is in snug engagement with the flesh of the patient, a vacuum is created in the chamber 16, which is sufficient to hold 25 the applicator on the patient at the desired location.

The function of the screen 24 is three-fold. In the first place it avoids excessive pains in the afflicted part of the patient by preventing the drawing of the skin and flesh of the patient into the casing 10, as can readily be understood. In the second place, it has been found by experiment that the screen 24 is probably the only means 30 which will permit the holding of the applicator in position with a partial vacuum in the chamber or pocket 16, probably because the flesh of the patient is not drawn taut about the edge of the attaching ring 20, as the flesh is prevented by the tightly stretched screen 24 from being drawn into a mass within the casing 10. In the next place the screen 24 is a conductor of electricity, and in this respect may cooperate 35 as a part of the electrode in distributing the current over the entire face area of the electrode, so that the entire portion of the person's anatomy to which the electrode is applied may be beneficially treated.

65 The pad portion 23, which is absorbent, is

used to support a liquid to render the same a conductor of electricity. The liquid may vary, according to the type of affliction to be treated, and may be water, copper sulphate, cocaine, salicylic acid, or the like. 70 The liquid supported in the absorbent portion 23 may most generally be an antiseptic, or a pain allaying liquid, such as cocaine. Where direct current is being used, and it is desired to apply a negative electrode to the patient, the cloth 23 will have to be used, if it is desired to support an antiseptic liquid thereon. However, in connection with the positive electrode where direct current is used, it is not necessary to supply an antiseptic substance, as the positive electrode has an antiseptic influence in connection with the application. Where, however, alternating current is used it is necessary to support an antiseptic in the absorbent portion 75 23, as neither of the electrodes where such current is used will have the antiseptic effect above noted.

Referring to the form B of this invention, the casing 10 thereof preferably includes the stamped metal portion 30, which provides the chamber 31 therein, and has centrally attached to the top thereof a tube 32, defining a passageway 33 which communicates with the chamber 31, and to which tube the portion 28 of the vacuum creating means E may be attached, substantially as is illustrated in Figure 3 of the drawings. The casing 10 is preferably of metal, and may have a terminal screw 34 exteriorly attached thereto for the connection of a conducting wire 35 thereto. The outer face of the casing 10 provides an annular seat 36, within which the pad 11 may be disposed. A pad supporting plate 35 may be carried within the chamber 31 of the casing 10, upon an annular seat 37 just inwardly of the seat 36; said supporting member 35 preferably having openings 38 therethrough so that the vacuum may act 40 through the pad 11. This supporting plate or member 35 may be constructed of cardboard or the like, and maintains the pad 11 in a definite plane against sliding into the chamber 31 during an application of the 45 electrode B. The pad 11 of the form B of invention preferably includes the superposed layers of fabric or cloth 40, and the outer fine mesh copper screen 41, which is 50 tautly stretched over the exposed face of the pad 11, much in the same manner as the screen 24 for the form of invention above described, and which cooperates in the manner above set forth during an application of 55 the electrode B.

Referring to the form of electrode C, the casing portion 10 thereof is preferably polygonal in plan view. This casing 10 includes the top plate 45, with the depending outer side walls 46. The top wall 45 also sup-

ports the depending inner walls 47, which are arranged parallel to and in spaced relation with the outer walls 46, to provide a peripheral chamber or pocket 48 extending above the margin of the casing 10; this pocket or chamber 48 being open on the lower face of the casing 10 and over which a screen 50 is disposed at the attaching side of the casing 10. A tubular extension 51 communicates through an outer wall 46 of the casing 10, and to which the tube 28 of the vacuum creating means E may be attached to enable the formation of a vacuum in the peripheral groove or chamber 48. The compartment or pocket 53 defined between the inner walls 47, is adapted to receive the pad 11, which may be of the formation above described for the forms A and B of this invention, although there is no outer screen covering for the pad 11. A terminal binding member 55 may be carried by the top wall 45 of the casing 10, for the attachment of a conductor 56 to the casing 10.

The form D of this invention embodies somewhat of a novel principle, as the casing 10 thereof is preferably of insulating material, and defines a chamber or pocket 57 within which the vacuum is created. A lateral extension 58 projects from the head 59 of the casing 10, to which the tubular portion 28 of the vacuum creating means E may be attached to permit vacuum formation within the pocket 57. The pad arrangement 11 is adapted to seat in the enlarged portion of the pocket 57, in engagement with the annular walls 60 of the casing 10.

Referring to the construction of the pad 11 as utilized with the form D of the invention, the same may include a circumferential supporting ring 61, of copper or analogous material, to one outer marginal edge of which is secured the fine mesh screen 62. The fabric or absorbent portion 64 of the pad 11 is adapted to rest within the ring 61 upon the screen 62. A terminal binding post 65 is preferably supported by the insulation casing 10, in attachment with a conducting strip 66 located within the pocket or chamber 57; said conducting strip 66 leading over the inner surface of the casing walls 60 to contact with the metal ring 61, so that the current may flow through the fine mesh screen 62.

In connection with the pad 11, a sanitary cloth covering 70 may be used, which has been shown as applied to the pad 11 of the form of invention D. This cloth 70 is adapted for disposal over the face of the screen 62, having attaching strips 71 connected at the marginal edges thereof, which extend over the back or inside surface of the pad 11, and may be secured to a connecting member 72 upon the inside surface of the pad 11; the member 72 having prongs 73 thereon for the purpose of connection of the free

ends of the strips 71 thereto, substantially as is illustrated in Figures 6 and 8 of the drawings. It is to be understood that this sanitary covering 70 may be considered as a generic feature of this invention, as the application of the same may be made to all forms of electrodes herein described.

From the foregoing description of this invention it is apparent that an improved electrode has been provided, principally embodying a novel means for the effective attachment to a patient to properly support the same in position during treatment. As treatments in many instances extend over considerable periods of time it is obvious that the maintenance of the electrode on the patient by means of a vacuum created therein is an important feature, as it permits the operator to direct his attention elsewhere. It is of course understood that the operation and advantages resulting from this invention as above described for the form A of the invention are applicable to all forms of the invention.

Various changes in the shape, size, and arrangement of parts may be made to the forms of invention herein shown and described, without departing from the spirit of the invention or the scope of the claims.

I claim:

1. In an applicator the combination of a casing having a pocket opening outwardly, a porous pad fixedly mounted entirely across the mouth of said pocket, and means for forming a vacuum within said pocket behind said pad.

2. In a device of the class described the combination of a casing having a pocket therein opening at a side of said casing, a pad placed across the mouth of said pocket, a fine mesh conductor screen carried by the casing at the outer side of and across said pad, and means for creating a suction within the pocket of said casing at the inner side of said pad.

3. In an applicator of the class described the combination of a casing formed of insulating material having a pocket therein, a conductor screen mounted across the mouth of said pocket of said casing, means for creating a suction within the pocket, and means in connection with said screen for conduction of electrical current thereinto.

4. In an applicator of the class described the combination of a casing formed of insulating material having a pocket therein, a conductor screen mounted across the mouth of said pocket of said casing, means for creating a suction within the pocket, metallic connection from an external conductor to said screen for conduction of electrical current thereinto, and an absorbent pad carried within the pocket behind said screen.

5. In a device of the class described the

combination of a casing having a chamber therein, means for creating a suction within the chamber, a pad mounted within the casing across the mouth of said chamber, and 5 a sanitary covering detachably carried by said pad.

6. In a device of the class described the

combination of a supporting member having a pocket therein, means for creating a vacuum within the pocket, and a rigid screen 10 mounted over the mouth of said pocket to prevent the skin of the patient being drawn into the pocket.

WILLIAM E. MONTGOMERY.
